UNITED STATES PATENT OFFICE.

JAMES A. GRAHAM, OF MILWAUKEE, WISCONSIN, ASSIGNOR TO THE MILWAUKEE HARVESTER COMPANY, OF SAME PLACE.

BINDER-SHIFTING MECHANISM.

SPECIFICATION forming part of Letters Patent No. 397,356, dated February 5, 1889.

Application filed November 14, 1887. Serial No. 255,039. (No model.)

To all whom it may concern:

Be it known that I, JAMES A. GRAHAM, of Milwaukee, in the county of Milwaukee, and in the State of Wisconsin, have invented certain new and useful Improvements in Binder-Shifter Mechanism; and I do hereby declare that the following is a full, clear, and exact description thereof.

My invention relates to harvesters and binders; and it consists in improved mechanism for shifting the binder, which will be fully described hereinafter.

In the drawings, Figure 1 is a plan of a harvester and binder embodying my invention. Fig. 2 is a front elevation of the same. Fig. 3 is a section on line X X, Fig. 1. Figs. 4 and 5 are details. Fig. 6 is an elevation from the stubble side of the harvester, showing the supports for the binder-deck.

20 A is the binder-deck, whose upper edge is loosely supported on a strip, *a*, that is secured to suitable brackets, *a'*, that project from the elevator-frame *B*, and adjacent to its lower front edge the said binder-deck is secured to the upper end of an arm, *b'*, which arm is secured to and projects up from the gas-pipe *C*, that forms part of the binder-frame, the said upper end of said arm *b'* being preferably shaped to receive and be attached to a 25 strengthening-strip, *b*, secured to the under side of said binder-deck. The lower portion of the binder-deck from about its center to its rear edge rests upon and is secured to the binder-frame in the usual manner. This gas-pipe *C* is supported near the rear end of the harvester by braces *d d*, that project from the cross-truss *D D* of the harvester-frame, the two braces *d d* intersecting to form a loose bearing for the gas-pipe to slide in; and at its 30 opposite end this gas-pipe is supported in a bearing, *e*, in a standard, *f*, that projects up from an arm, *g*, on the lower front stubble corner of the harvester-frame, and this standard is braced by a strap, *g'*, to the truss *D*, as well as by a rod, *h*, that extends from 35 near its upper end to the upper portion of the elevator-frame, as shown clearly in Fig. 2.

E is a hood, preferably of sheet metal, that is secured at one edge to the upper portion of 40 the elevator-frame, so that its opposite edge

will project over the binder-deck toward the standard *F* and arm *G* of the binder-frame, which carry the knotter-shaft *H*.

A gas-pipe, *I*, is rigidly suspended between the hood *E* and sleeve *G*, and parallel to them, 55 by a brace, *i*, that extends from one end of the said gas-pipe to the standard *F* and braces *j k k*, that extend from said gas-pipe to sleeve *G*, and this pipe runs through a bearing, *L*, in an arm that projects from the intersecting 60 ends of two diagonal braces, *m n*, that are secured to the hood *E*, which forms a part of the harvester, and said bearing *L* is preferably formed by bifurcating the arm of the two braces *m n* horizontally to form jaws that are 65 internally concaved to conform to the shape of the gas-pipe, which jaws are held together to form the bearings for the gas-pipe *I* by suitable bolts or rivets, and either or both of these bolts or rivets may form the axle or 70 axles of a roller or rollers, *O*, which may be interposed to facilitate the sliding of the gas-pipe *I*, which forms a guide-bar. A lever, *M*, is pivoted to the brace *m*, and one end of this lever is connected by a rigid link, *p*, with the 75 binder-frame through brace *i*, while its other end forms a handle and carries a pawl, *q*, for engagement with the teeth of a rack-brace, *r*, one end of which is secured to each of the 80 braces *m n*.

The driving or packer shaft *P* is hung from the binder-deck in the usual manner, as shown in Fig. 3, and shifts with the binder, as is usual, and the sprocket-wheel *S*, which is splined on shaft *P*, is prevented from shifting 85 with it by a spanner, *T*, that projects up from a standard, *U*, that in turn is secured to the truss *D*. The arms of the spanner *T* enter a groove in the hub of the sprocket-wheel *S* and hold it in position above the driver-sprocket 90 without interfering with its revolution.

The needle-shaft (not lettered) has its bearing, as usual, in the lower horizontal arm of the binder-frame, and the packer-shaft has the usual location of the packer-shaft in grain-binders.

The operation of my device is very simple, and is as follows: When the binder is to be shifted, the lever *M* is released by withdrawing the pawl *q* and moving the handle of the 100

lever to the right or left to draw or thrust the binder in the desired direction, the lever M acting on link p, which in turn acts upon the frame F G of the binder, the parts being centered and prevented from cramping by the gas-pipe I and its bearing L, which bearing L also sustains some of the weight of the binder and causes it to move freely over its lower supports.

- 10 The brace i extends directly from the standard F to the adjacent end of the pipe I. The braces k extend from the pipe I, one slightly upward to an ear on the upper side of the sleeve G, and the other to a like ear on the 15 under side, while the brace j extends diagonally from the junction of brace i and pipe I to the upper lug on the sleeve G, to which the outer end of upper brace, k, is attached.

Having thus fully described my invention, 20 what I claim as new, and desire to secure by Letters Patent, is—

1. The combination, with the binder-frame and deck, of the elevator-frame, and braces

extending therefrom over the binder-deck and forming a bearing, a guide-bar braced to the 25 binder-frame and adapted to slide in said bearing, and a lever pivoted on the harvester and connecting it with the binder-frame, substantially as described.

2. The combination, with the binder-frame 30 and deck, of a hood extending from the elevator-frame, braces extending from the hood and forming a bearing, a guide-bar braced to the binder-frame and adapted to slide in said bearing, and a shifting-lever pivoted to the 35 hood and connecting it with the binder-frame, substantially as described.

In testimony that I claim the foregoing I have hereunto set my hand, at Milwaukee, in the county of Milwaukee and State of Wisconsin, in the presence of two witnesses.

JAMES A. GRAHAM.
